[57] CLAIM

The ornamental design for a gas detector, as shown and
described.

DESCRIPTION

FIG. 1 is a top, front and left side perspective view of a
gas detector showing my new design, with the flexible
gas probe in an extended position;

FIG. 2 is a top, front and left side perspective view,
with the flexible gas probe in a mounted position;

FIG. 3 is a front elevational view of FIG. 2;

FIG. 4 is a right side elevational view of FIG. 2;

FIG. 5 is a left side elevational view of FIG. 2;

FIG. 6 is a rear elevational view of FIG. 2;

FIG. 7 is a top plan view of FIG. 2; and

FIG. 8 is a bottom plan view of FIG. 2 thereof.

FIG. 2

FIG. 1

FIG. 3

FIG. 4

FIG. 5

FIG. 6

FIG. 7

FIG. 8
